UNITED STATES PATENT OFFICE.

WILLIAM H. WILKINSON, OF NEW YORK, N. Y., ASSIGNOR TO NORTH
AMERICAN IRON WORKS, OF NEW YORK.

DESIGN FOR A VASE.

Specification forming part of Design No. 6,384, dated February 4, 1873.

To all whom it may concern:

Be it known that I, WILLIAM H. WILKINSON, of Brooklyn, Kings county, New York, have invented and produced a new and original Design for a Vase, of which the following is a specification:

Its most appropriate application is to large vases of cast-iron adapted for use in gardens, yards, and analogous situations. It may, however, be made of any size and material for indoor or outdoor use. It may be used with or without provisions for jetting water to form a fountain.

The nature of my design is fully represented in the accompanying photographic illustrations, which form a part of this specification.

Figure 1 is a side view, and Fig. 2 a plan view.

The bowl or body is formed with a gracefully-curved contour, with an overhanging bor-

der of leaves, under which is a closely-wrought belt in relief of the decorations known as Grecian egg. Below this the body has a smooth ground, on which appears, in relief, vines and flowers. The pedestal or support is spread at the foot, and decorated with boldly-raised acanthus leaves. The nearly-conical foot is surmounted by a bead, and above this is an overhanging ornament of tastefully wrought leaves, corresponding nearly to the Grecian honeysuckle, but with rounded points.

I claim as my invention—

The design for a vase, as shown.

In testimony whereof I have hereunto set my hand this 28th day of December, 1872, in the presence of two subscribing witnesses.

WILLIAM H. WILKINSON.

Witnesses:

W. C. DEY,

ALF. WESTBROOK.
